CONTROL MECHANISM FOR WEIGHTLESS
WINDOW SASHES

Joseph Sciacca, New York, N. Y.

Application October 29, 1947, Serial No. 782,819

4 Claims. (Cl. 16—193)

1

This invention relates to weightless windows and especially to sash control means for retaining the sashes of a window in any attained positions while allowing said sashes to be manually raised or lowered, at will.

The main object of my invention is to simplify the construction of windows having movable sashes and also to save material and space by avoiding the necessity of using a pair of iron sash weights for each sash and extra wood or metal for enclosing said weights.

Another object is to provide a sash control mechanism which simultaneously controls one side of two sashes.

A further object is to provide such sash control mechanism which takes up a minimum of space and is easily installed, even in limited quarters.

A yet further object is to provide a pair of such mechanisms for each window at low cost and of reasonably simple construction, so that the same may be readily serviced or replaced when necessary.

It is also an object to introduce such sash control mechanisms which may be adjusted by an accessible adjustment means.

Other objects and advantages of the invention will appear in further detail as the specification proceeds.

In order to facilitate comprehensive appreciation of the present invention and its features, the same is illustrated in a practical embodiment in the accompanying drawings forming part hereof, and in which,

Figure 1 is a fragmentary perspective view of a window equipped with sash control mechanisms according to the invention, the sashes being of the weightless type;

Figure 2 is a partial section taken vertically on line 2—2 in Figure 1;

Figure 3 is an enlarged fragmentary view of the mechanism and adjacent sash portions partially shown in Figure 2, certain portions of the window frame being removed to reveal details;

Figure 4 is a horizontal section of the same on line 4—4 in Figure 3;

Figure 5 is a vertical section taken on line 5—5 in Figure 4;

Figure 6 is another vertical section taken on line 6—6 in Figure 4, the parts being arranged as also shown in Figure 3;

Figure 7 is a rear view of the sash control mechanism appearing in Figure 6.

Throughout the views, the same or like reference numerals indicate the same or like parts.

2

It is common experience to find it necessary to repair broken sash cords, and even when sash chains are used, repairs and adjustments are sometimes necessary. In each case, the window

frame must be opened at the sides in order to obtain access to the sash weights, and time is lost and partial defacement of the window frame occurs which must then be patched and painted to cover the broken or scratched surfaces. It is

10 obvious that in a conventional window having its two sashes counterbalanced by sash weights, four weights to the window, the latter weights form a serious loss of metal withdrawn from the market, while the wood casing forming part of the

15 window frame also forms a waste of wood which could have been used for other and more essential construction. In addition, the space required to house the sash weights and allowing for their vertical travel could well be occupied by

20 firm wall structure and is thus waste space. All these features of the conventional type of window construction belong to a more leisurely and wasteful age, and hence call for replacement by modern means.

25 I have found that it is possible to eliminate the sash weights, sash cords or chains and portions of the window frame housing them, and instead introduce two small sash control mechanisms in the sides of the window frame on a simplified

30 window, so that the construction of the latter is more compact and uses less material and space than heretofore.

Thus, in the practice of my invention, and referring now again to the drawings, a window frame, generally indicated at 9 has a pair of sashes 10 and 11 adapted to be raised and lowered in said frame in conventional manner. As may be seen best in Figure 2, the bottom 12 of upper sash 10 forms a closure with the upper portion 13 of lower sash 11, the sashes being guided in well known manner by inner and outer strips 14 and 15, while the two are separated by a pair of aligned intermediate strips 16, 17, the guide and separating strips being similar at both

40 sides of the window frame. As other features and details also correspond at both sides, the mechanism and features of the left side of the window will be described and should be understood as repeated in detail at the right side of the same window and its frame.

45 At the point between the ends of the intermediate strips 16 and 17, at the level of the lower end 12 of the upper sash and the upper end 13 of the lower sash, is located an inner guide roller 18 engaging

50 55 against sash 11, while exteriorly of sash 10 is a

similar guide roller 19, both rollers forming portions of a control mechanism mounted on an anchor plate 20 shown in Figures 3 to 6, which is normally screwed or fastened to the side 21 of the window frame beneath strips 14 and 15. The rollers rotate upon a pair of studs 22, 23 fixed upon plates or brackets 24, 25 at the rear of anchor plate 20, bracket 25 being directly secured to plate 20 by means of rivets or screws 26, 26. The studs in both cases pass through anchor plate 20, stud 22 having a clearance slot 27 in said plate to allow movement of bracket 24 (Figure 4) and this bracket having a pair of rigidly attached studs 28, 29 extending through a pair of guide slots 30, 31 in the anchor plate 20. Intermediate roller 18 and said anchor plate is mounted a cover plate 32 for covering the studs 28, 29 and their slots 30, 31, and normally itself being covered by window strip 14, and only exposing the roller. The purpose of the two rollers is to hold the sashes in line with their proper movement up and down, and especially to hold them against the main operating portions of the sash control mechanism now to be more minutely described, but in order to effect this purpose, bracket 25 has a pair of lugs 33, 34 and bracket 24 the lugs 35, 36, all forming bearings for an adjusting shaft 37. To lugs 34 and 35 is attached a tension spring 38 tending to draw bracket 24 toward bracket 25, the tension of said spring being adjustable by manually rotating shaft 37 by means of a finger wheel 38 exposed through slot 39 in plate 20, the inner end of this shaft being threaded at 40 and engaging in a nut 41 mounted or formed within lug 34 of bracket 25. A compression spring 42 is mounted upon the shaft between the finger wheel 38 and takes against lug 36 of bracket 24 so that this bracket tends to be pushed thereby toward bracket 25, and thus roller 18 is pressed against sash 11.

In the control mechanism, a group of screws or studs secured to plate 20 at 43, 43, etc., supports a smaller frame plate 44 in spaced relation to plate 20 just mentioned, and between these two plates are fixed two screws or studs 45, 45 spaced a short distance apart and extending through slots 46, 46 in a double pointed pawl 47, mounted upon said studs between the plates. Upon the facing edges of sashes 10 and 11 are attached rack strips 48, 49 having spaced teeth 50, 50, etc., with which the pawl is adapted to engage simultaneously on both sashes, the feature of roller 18 with its mounting being adapted to shift resiliently facilitating the movement of the sashes and momentary jumping of the pawl past the teeth 50 in either rack strip while forcibly shifting either sash by hand. In order to prevent jamming or binding, and instead maintaining the proper spacing between the sashes without friction, a spacing ring or roller 51 is also mounted loosely about the studs 45 and prevents the pawl from entering unduly far between the rack teeth; this roller 51 thus serving, as it were, as an anti-friction roller bearing between the two sashes. A spacing block 52 serves to space the parts in most advantageous position, the studs 45 extending through said block and the latter being secured to plate 20.

The two intermediate studs 43 also serve as fulcrums for a pair of corresponding rocking yokes 53, 54 enveloping portions of the pawl and ring just described, each yoke having a pair of ball bearings 55, 55 spaced apart a distance which causes both balls in each yoke to register with spaces between teeth 50 of the rack strips 48 and

49 on both sashes. These yokes virtually form ball cages for the ball bearings and are mutually spaced just far enough apart upon studs 43, 43 to allow each to clear the other during upward or downward movement of the sashes.

When a sash is to be raised, the pawl 47 and also the ball bearings in the yoke pertaining to that sash tend to resist the movement, but when sufficient force is applied, the pawl and also the ball bearings mentioned will jump the teeth in the corresponding sash rack strip until the sash is stopped in desired position, at which time the balls and pawl will instantly enter the spaces between the teeth adjacent thereto and will definitely prevent any accidental dropping or shifting of the sash.

Manifestly, variations may be resorted to and parts and features may be modified or used without others within the scope of the appended claims.

Having now fully described my invention, I claim:

1. In a mechanism for weightless window sashes, in combination, a frame, a pair of sashes, a support unit on said window-frame, toothed rack strips on opposingly facing sides of said sashes, a movable pawl on said support unit immediately disposed between said sashes and said strips thereon so as to engage said teeth thereon, said unit comprising auxiliary roller means disposed between said sashes so as to engage intermittently depressions between said teeth on said strips, and means on other sides of said sashes, facing said frame, said means being adapted to glidably move said sashes from opposite directions toward said pawl.

2. In a mechanism for weightless window sashes, the combination according to claim 1, wherein said means comprises a fixed plate on said unit, and adjustable plate slidably movable within slots in said unit, studs on said respective plates, rollers on said studs, glidably engaging the outer sides of said sashes, lugs on said respective plates, a shaft extending through said lugs, said shaft having a threaded end in engagement with a respective one of said lugs, spring means surrounding said shaft holding said plates in spaced relation with respect to each other and a fixed adjusting wheel on said shaft to rotate the same and thus vary the respective distance of said lugs, said studs and said rollers with respect to each other so as to exert opposed pressure thereon upon said sashes and said pawl therebetween.

3. In a mechanism for weightless window sashes, in combination, a support member on the window frame, a pair of toothed rack strips on respective window sashes, means to resiliently move said sashes towards each other, a movable pawl on said support member, said pawl projecting into the space between said sashes and said toothed rack strips so as to engage respective teeth thereof, simultaneously, a rocking yoke on said support member extending above and below said pawl, said yoke comprising ballcages and ballbearings therein, so disposed between said sashes as to engage and glidably space apart said strips and said sashes, and a spacing ring under said pawl to maintain said sashes in spaced apart relation with respect to said pawl and said yokes.

4. In a mechanism for weightless window sashes, the combination according to claim 3, wherein said spacing ring and said pawl on one hand, and said resilient means on the other hand effect pressure upon said sashes in opposing directions, so that normally said pawl will fasteningly en-

gage opposite teeth on said strips thus maintaining said sashes in fixed position, while, when said sashes are forcibly displaced, said yokes by means of said balls will enlarge the distance between said strips and thus disengage said pawl from said respective teeth.
